UNITED STATES PATENT OFFICE.

WILLIAM D. McDONOUGH, OF EL PASO, TEXAS, ASSIGNOR OF ONE-HALF TO EVER P. MORGAN, OF EL PASO, TEXAS.

EMBROIDERING ATTACHMENT FOR SEWING MACHINES.

Application filed June 27, 1923. Serial No. 648,092.

To all whom it may concern:

Be it known that I, WILLIAM D. McDONOUGH, a citizen of the United States, residing at El Paso, in the county of El Paso and State of Texas, have invented a new and useful Embroidering Attachment for Sewing Machines, of which the following is a specification.

This invention relates to an embroidering attachment for sewing machines, one of the objects of the invention being to provide a normally stationary needle for engagement by the tread used upon the work, there being a movable thrusting element or "looper" operating with the needle and with a yieldable work support whereby, during each action of the looper, a portion of the strand acted on will be forced through the fabric being worked, thereby to provide a loop.

20 A further object is to provide a movable looper cooperating with a yieldable work support for the purpose of moving the work intermittently during the reciprocation of the looper.

25 A still further object is to provide an attachment of this character which can be applied readily to an ordinary sewing machine, which is inexpensive, and will operate efficiently to produce any desired embroidery designs upon a properly held fabric.

30 A still further object is to provide a structure which is capable of slight modifications to adapt it for use with all kinds and sizes of threads, with strands of rags, and various other materials for use in ornamenting fabrics of all kinds.

With the foregoing and other objects in view which will appear as the description 40 proceeds, the invention resides in the combination and arrangement of parts and in the details of construction hereinafter described and claimed, it being understood that changes in the precise embodiment of 45 the invention herein disclosed may be made within the scope of what is claimed without departing from the spirit of the invention.

In the accompanying drawings the preferred forms of the invention have been shown.

In said drawings

Figure 1 is a side elevation of the attachment, a portion of the yieldable work support being in section and the adjacent parts

of a sewing machine being indicated by broken lines.

Fig. 2 is a plan view of the attachment, adjacent parts of a sewing machine being indicated by broken lines. 60

Fig. 3 is a section on line 3—3, Fig. 1.

Fig. 4 is a view similar to Fig. 1, showing a slightly modified structure.

Fig. 5 is a bottom plan view of the needle, its holder, and the looper illustrated in 65 Fig. 4.

Fig. 6 is a section on line 6—6, Fig. 4.

Referring to the figures by characters of reference, 1 designates an attaching plate that can be formed with a slot 2 near one 70 end to receive a clamping screw 3 whereby the plate can be held to the top of a sewing machine in proper position relative to the head A of the machine. Extending from the plate 1 is a bow spring 4 constituting 75 a yieldable work support and in the structures shown in Figs. 1 and 2, this spring is formed integral with plate 1 although it is to be understood that any other construction can be used. The spring has its concaved face lowermost and has a longitudinal slot 5 adapted to be located directly under the working parts of the attachment hereinafter described. The free end of the spring 4 is preferably upturned as indicated at 6 so that, when the spring is depressed, this upturned portion can contact with and readily slip along that portion of the surface of the sewing machine directly under the spring. 80

The shank S usually provided for the presser foot of a sewing machine is utilized in the present instance for holding the stationary needle of the attachment. The usual presser foot is adapted to be removed from the shank S and a clamping sleeve 7 is placed on the shank and secured thereto by means of a screw 8. An arm 9 extends from this sleeve and has its free end bent laterally to provide a flange 10. To this flange 100 is secured, by means of screws 11 or the like, one side portion of a plate 12 in one face of which is formed a longitudinal channel 13. This channel is made by pressing the middle of the plate backwardly or out of line along the longitudinal center of the plate, there being left a projection or needle point 14 at the lower end of the depression 13. An eye 15 is provided in this projecting point for receiving the strand of 110

silk or other material to be used in working a fabric.

Instead of using an ordinary needle on the reciprocating needle bar B of the sewing machine, there is provided an ear 16 adapted to be fastened to the side of the bar by the means of a screw 17 or in any other suitable manner. This ear is integral with a plate 18 preferably disposed at a right angle to the 10 ear and supported where it will work or reciprocate upon the recessed front face of the plate 12 when the bar is being reciprocated. Extending downwardly from the plate 18 is a finger 19 inclined downwardly 16 and backwardly so as to fit snugly within the depression 13 as indicated clearly in Figs. 1 and 2.

It is to be understood that the parts herein described can be connected readily to a sewing machine and after they have been properly assembled and adjusted, the work to be embroidered is placed in an embroidery hoop and inserted between the stationary needle and the spring 4. After the work has 20 been properly placed the sewing machine is operated in the usual manner, it being understood of course that a thread to be used in working the fabric is inserted through the opening or eye 15. Each time the finger 19 25 moves downwardly it engages the thread that is extended through the opening 15 and thrusts it downwardly through the fabric supported by the spring 4. This downward movement of the finger or looper 19 will result in the depression of spring 4 as well as 30 the fabric engaged thereby and this depression will result in the fabric going below the needle point allowing the hoop to move to position for the next loop. The movement 35 will also produce a slight backward feeding of the engaged fabric so that when the finger or looper 19 is removed upwardly from the fabric, leaving a loop of the thread underneath the fabric, the fabric will be positioned to receive another loop at a different 40 point close to the loop previously formed. Thus a line of loops can be made along the fabric, it merely being necessary to guide the fabric in order to insure formation of 45 the loops along a selected line. The feeding of the fabric is automatic as long as the fabric is left free to move under the cooperation of the looper 19 and spring 4. By slightly 50 retarding the movement of the fabric, the 55 loop is bunched or tightened. By slightly drawing or shifting the fabric during the operation of the attachment, a short loop will be formed giving the effect of what is known as a "French knot."

60 By providing loopers or fingers 19 of different lengths, different results can be obtained. For example, a "chenile" effect or a "velvet" effect can be obtained. It is not necessary to change the needle 14 at any 65 time.

Obviously the attachment can be so proportioned as to adapt it for use in looping strips of rags, in the manufacture of rag rugs and the like.

As shown in Fig. 3, the needle can be 70 formed with a series of openings or eyes 15 of different sizes, thereby adapting the needle for use with threads of different sizes.

Figs. 4 to 6 inclusive illustrate a modified construction. This includes a sleeve 20 for 75 attachment to the presser foot shank S. This sleeve has a holding plate 21 secured thereto in any suitable manner or formed therewith, the forward end of the plate being downturned and forked as shown at 22. 80 To this forked downturned portion is connected the needle plate 23 having the depending point 24 for receiving a thread. A spring strip 25 is connected to the rear end of the plate 21 and extends under an opening 85 26 formed in the plate 21 directly under the reciprocating needle bar B of the head A. The free end of this spring strip is extended upwardly so as to normally be seated within the angle portion of the strip 21 and from this upper portion of the strip 25 is extended a finger 27 adapted to work within the forked depending portion 22 and against the plate 23. A looper finger 28 is extended 90 downwardly from the portion 27 and is 95 adapted to engage the thread extended through the needle point 24. A work supporting spring strip 29 similar to the one hereinbefore described is provided under the looper 28 and the needle point 24. When a 100 fabric to be worked is placed over the strip 29 and the sewing machine set in motion, the bar B will work through the slot 26 and engage and depress the strip 25, thereby causing the looper 28 to operate in the same 105 manner as hereinbefore described. Each time the bar B moves upwardly the spring strip 25 will of course elevate the looper.

What is claimed is:—

1. An embroidering attachment for sewing machines including a yieldable work support, a stationary needle adapted to be supported thereabove, and a looper for reciprocation above the work support and relative to the needle. 110

2. An attachment of the class described including a yieldable work support having an opening therein, a needle adapted to be held stationary and having thread engaging means, and a looper mounted for reciprocation upon the needle to intermittently engage a thread and force it through a fabric on the work support. 120

3. An attachment of the class described including a yieldable work support having an opening therein, a needle, means for holding the needle stationary above the work support, said needle having a thread engaging portion, there being a longitudinal depression within the needle, a looper ex- 125

tending into the depression, and means for supporting the looper for reciprocation relative to the needle.

4. The combination with the presser foot shank and needle bar of a sewing machine, of a needle, means for connecting the needle to the presser foot shank to support the needle in stationary position, a looper, means for connecting the looper to the needle bar for reciprocation therewith relative to the needle, and a yieldable work support below the needle and having an opening therein for the reception of the looper.
5. A device of the class described including an attaching plate, an apertured yieldable work support extending therefrom, a needle having a thread receiving opening, an arm, means for securing the arm to the presser foot shank of a sewing machine, means for detachably securing the needle to the arm, a looper mounted for reciprocation along the needle, and means for detachably securing the looper to the needle bar of a sewing machine.

6. A device of the class described including a yieldable work support having an opening, a needle, a member for attachment to the presser foot shank of a sewing machine, said needle being secured to the

member and supported thereby above the aperture in the support, and a looper mounted for actuation by the needle bar of a sewing machine, said looper slidably engaging the needle.

35

7. An attachment of the class described including a yieldable work support having an opening therein, a needle, means for supporting the needle fixedly above the opening, said needle having a series of openings for the reception of threads of different sizes, a member mounted for actuation by the needle bar of a sewing machine, and a looper extending in said member and slidably engaging the needle along a line intersecting the openings in the needle.

40

8. The combination with a needle and means for fixedly supporting the same, of a looper mounted for reciprocation along the needle, and a yieldable support cooperating with the looper for feeding work across the end of the needle and for yielding under the pressure of the looper.

45

In testimony that I claim the foregoing as my own, I have hereto affixed my signature in the presence of two witnesses.
